UNITED STATES PATENT OFFICE.

WILLIAM A. WELLS, OF SPOKANE, WASHINGTON.

WALL STRUCTURE.

Application filed July 17, 1923. Serial No. 652,025.

To all whom it may concern:

Be it known that I, WILLIAM A. WELLS, a citizen of the United States, residing at Spokane, in Spokane County, and State of Washington, have invented certain new and useful Improvements in Wall Structures, of which the following is a specification.

My present invention relates to improvements in wall structures of that type built up of solid, angular, blocks, which are interlocked and retained in position within the structure by the interlocking members. The primary object of the invention is the provision of a set of blocks of this type that are comparatively inexpensive in cost of production and which may be laid in courses by unskilled labor to form strong, durable and well braced wall structures for dwellings and other buildings. By the utilization of my invention walls may quickly and accurately be erected to form permanent structures and provided with air spaces for insulation against the transmission of heat and moisture, thus insuring a dry and sanitary building adapted for either warm or cold climates.

In carrying out my invention I utilize a specially formed and manufactured set of blocks which may approximate in size the standard bricks now in use, and the blocks are adapted for the erection of double wall structures with a single air space between them as well as for double wall structures with an intermediate partition and double air space.

The invention consists essentially in certain novel features of construction in the blocks and in novel combinations and arrangements of the blocks to insure a well braced, strong, and durable wall structure, as will hereinafter be more fully described and claimed.

In the accompanying drawings I have illustrated three forms of wall structure built up or erected from the blocks in which the blocks are combined and arranged according to the best modes I have so far devised for the practical application of the principles of my invention.

Figure 1 is a perspective view of one of the wall blocks.

Figure 2 is a perspective view of one of the tie blocks with the interlocking elements for co-action with the wall blocks.

Figure 3 is a perspective view of another form of tie block.

Figure 4 is a perspective view showing a portion of a double wall structure with a single air space between, and illustrating the use of the tie blocks.

Figure 5 is a perspective view showing the use of the tie block of Fig. 2 where a comparatively wider air space is required.

Figure 6 is a view showing the manner of erecting a wall structure with double air space.

The blocks are preferably made up of concrete material in rectangular, oblong form or shape, and the wall blocks 1 approximate the standard building bricks in dimensions in order that they may be conveniently handled and laid in courses similar to the manner of laying bricks. The wall blocks are all of similar structure, but some of them may be provided with finished surfaces to form the exterior face of a building wall, while the interior faces of the interior shells of a double wall are adapted to receive mortar or plaster as usual.

Each wall block as shown in Figure 1 is provided with a top, longitudinally extending, centrally located rib 2 preferably rounded on its exterior surface, which merges into a vertically extending rib 3 at one end of the block, also centrally located. At its opposite end the block is fashioned with a complementary vertically extending groove 4, while the underside of the block is fashioned with a rounded groove 5 extending longitudinally thereof and complementary to the longitudinal rib 2 at the top of the block. The wall blocks are molded or otherwise fashioned in identical molds and are therefore of identical formation and adapted to be laid in courses as A and B in Figure 4 with the ribs fitted in their complementary grooves and extending longitudinally of the courses.

The tie block 6 of Fig. 3, which is adapted for use in the single air-space structure of Figure 4 and the double air-space structure of Fig. 6 is disposed transversely of the wall

structure and interposed between adjoining wall blocks of each course. Thus the butt end of the transverse tie block occurs at regular intervals throughout the length of the courses to break the monotony that would otherwise exist in the appearance of the wall structure.

The tie blocks are of suitable size with their depth corresponding to the height of the wall blocks, and as seen in Fig. 3 each tie block 6 has near its ends a transverse top rib as 7, 7 which merges into a vertical rib 8 extending down one side of the tie block. And the remaining two sides of the block are

fashioned with complementary grooves 9 and 10, the latter being formed across the under face of the block. An inspection of Fig. 4 will show that the ribs 2 of the wall blocks and ribs 7, 7 of the tie blocks are

aligned in the wall structure and the grooves 5 of the wall blocks are aligned with the grooves 10 of the tie blocks. In this manner the courses of blocks are joined and locked against lateral movement. The end ribs 3 and end grooves 4 of the wall blocks are adapted to interlock with the end grooves 9 and end ribs 8 of the tie blocks to brace and hold the inner and outer shells A and B of the wall structure.

In the erection of the single air-space structure of Fig. 4 and the double air-space structure of Fig. 6 a suitable foundation is of course provided and the wall blocks and tie blocks are laid in courses as indicated.

In Fig. 6 three shells are shown as an inner shell C, an intermediate partition D and an outer shell E between which are provided two air spaces adapting the wall structure for certain uses.

In the structure of Fig. 5 two shells A and B are erected in courses from the wall blocks 1, and the modified form of tie block 11 is introduced for use, in pairs, one block of the pair being interposed in the inner shell and the other block of the pair being interposed in the outer shell of the wall structure.

In Fig. 2 it will be seen that the tie blocks 11 are provided with top ribs 12 12 and side ribs 13 13 near their ends, and with complementary grooves 14 and 15 in their sides and bottoms. Intermediate ribs 16 and 17 are also fashioned on these blocks and complementary grooves 18 and 19 are provided in the remaining faces of the blocks. Thus in Fig. 5 two of these tie blocks are designated as 11^a and 11^b respectively the former laid on the latter with its end interposed between the course in shell A and the block 11^b with one end interposed in the course of the shell B. Within the air space these tie blocks lap and the intermediate top rib of the block 11^b fits within the complementary groove 15 of the block 11^a, while the intermediate groove 19 of block 11^a fits over

the complementary rib 12 of block 11^b. The tie blocks are thus locked together and their remote ends are locked in the respective shells A and B of the wall structure.

In Figure 5 the tie blocks 11^a and 11^b at 70 their adjacent portions are indicated as having been dipped in a water-proofing material such as asphaltum to form a coating or film thereon which prevents transmission of moisture from one wall section or shell 75 to the other. A bonding material such as plastic asphaltum may be applied by a brush to the contacting surfaces of the adjoining blocks before they are laid in the wall which material also renders the joints air tight and 80 waterproof to prevent penetration of moisture through the wall.

The air spaces between the wall sections or shells may be filled with cinders to provide an insulated structure, or the spaces 85 may be filled with concrete or similar material for bonding the sections to provide a substantial monolithic structure. In the erection of fruit storage or ware houses the walls may be made frost-proof by the use 90 of a filling of shavings, ground cork or other well known insulating material. In some instances the spaces between the sections may be filled with suitable material, or where the double air-space or a plurality of 95 air-spaces are used one of the spaces may be left open as an air space, while another is filled with the material mentioned.

Whether the spaces are filled with such material or left open, it will be apparent 100 that a strong, durable and substantial wall structure is provided and economy in erection is secured because of the substitution of cheaper material when a filler is used, and when a filler is not used a further reduction in cost is attained.

The blocks may be molded from plastic material as concrete or fashioned as a clay product and burned in a kiln in the same manner that ordinary brick is produced. 110 The blocks may be produced in standard sizes as desired.

Having thus fully described my invention, what I claim as new and desire to secure by Letters Patent is—

1. In a wall structure a pair of parallel courses laid in courses and comprising superposed blocks having complementary grooves and ribs on opposite horizontal faces and complementary ribs and grooves on opposite 120 ends, and rectangular tie blocks connecting said sections, each said tie block having near its ends a pair of lateral ribs on two adjoining faces and a pair of lateral grooves on the other two adjoining faces, said ribs and grooves at the respective ends of the tie blocks being in the same transverse plane of the tie blocks.

2. In a wall structure a pair of parallel sections laid in courses and comprising 130

superposed blocks, said blocks having complementary grooves and ribs on opposite horizontal faces and complementary ribs and grooves on opposite ends, a pair of overlapping tie blocks connecting said sections, each said tie block having near its respective ends and intermediate thereof a pair of

lateral ribs on two adjoining faces and a pair of lateral grooves on the other two adjoining faces, for interlocking as described.

In testimony whereof I affix my signature.

WILLIAM A. WELLS.
